(57) **CLAIM**

The ornamental design for a bottle, as shown and described.

DESCRIPTION

FIG. 1 is a front view of a bottle showing my new design (with the back view and both side views being the same), shown as opaque;

FIG. 2 is a perspective view of the bottle shown in FIG. 1; FIG. 3 is a top view of the bottle shown in FIG. 1; and, FIG. 4 is a bottom view of the bottle shown in FIG 1. The evenly-dashed broken lines in the drawings showing the bottle pour spout, top portion of the bottle neck, and the bottom surface recess illustrate the portions of the design that form no part of the claim. The short dash-long dash broken lines in the drawings define the bounds of the claim and form no part thereof.
